UNITED STATES PATENT OFFICE.

GILBERT L. CROWELL, JR., OF ARLINGTON, NEW JERSEY.

DESIGN FOR A BACK FOR MIRRORS, BRUSHES, OR SIMILAR ARTICLES.

No. 37,564.

Specification for Design.

Patented Sept. 26, 1905.

Application filed March 11, 1904. Serial No. 197,716. Term of patent 14 years.

To all whom it may concern:

Be it known that I, GILBERT L. CROWELL, Jr., a citizen of the United States, residing at Arlington, in the county of Hudson, State of New Jersey, have invented a new, original, and ornamental Design for a Back for Mirrors, Brushes, or Similar Articles, reference being had to the accompanying drawings, which illustrate the design.

Figure 1 is a plan or elevation view of the

back or reverse side of the mirror, brush, or other similar article embodying my design. Fig. 2 is a side elevation of the same.

What is claimed as new is—

The ornamental design for a back for mirrors, brushes or similar articles as shown.

GILBERT L. CROWELL, JR.
